UNITED STATES PATENT OFFICE.

ROBERT W. HARPER, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed July 2, 1923. Serial No. 648,866.

To all whom it may concern:

Be it known that I, ROBERT W. HARPER, a citizen of the United States of America, residing at East Orange, in the county of 5 Essex and State of New Jersey, have invented certain new and useful Improvements in Telephone-Exchange Systems, of which the following is a full, clear, concise, and exact description.

10 This invention relates to telephone exchange systems, and particularly to those systems wherein mechanical switching apparatus is employed in the establishment of talking connections.

15 In exchange areas including both manual offices and automatic offices, where provision is made for the extension of calls made in a manual office to any of the outlying automatic offices, it is found desirable 20 in some cases to have the selective switches in the called automatic office controlled from the mechanism located at the calling manual office. By this plan the operator who first answers the call is enabled to establish the interoffice connection which leads 25 to a distant mechanical office without assistance, the entire operation of the switches at the distant office being governed by mechanism at the originating office controlled by 30 the answering operator therein.

At the manual office a plurality of operators' positions is provided, each of which has access to a plurality of groups of trunks, 35 one group leading to each of the distant automatic offices served. Each position is further equipped with a sender controlling keyboard, a set of office keys and a set of indicating lamps for trunk identification. There is also located at the manual office a group 40 of register senders common to the use of all operators, serving to control the movement of the switches in distant offices. In order that an idle sender may be taken for use to extend a call and to associate such sender 45 with the keyboard at the operator's position concerned, and also with an idle trunk in the particular group leading to the desired automatic office, a plurality of switching units is employed. Each unit comprises three distinct parts: a sender selector for selecting 50 an idle sender, trunk selectors for choosing an idle outgoing trunk and a plurality of operator's position selectors. These units are allotted successively for use so that an

operator desiring to extend a call takes the 55 allotted unit into service.

Since the total number of operators in the manual office greatly exceeds the capacity of a switch of the kind desirable for use as a position selector, the operators' positions are 60 divided into a plurality of small groups, and the position selecting mechanism of each unit accordingly consists of a corresponding number of separate position selector switches. This general organization 65 of mechanism as above outlined forms the basis of a Patent No. 1,513,362, issued to L. M. Allen, October 28, 1924. In order, however, that the operators of any group of 70 positions may not monopolize allotted switching units as fast as they become allotted for use, it is desirable to provide some means for giving the operators' positions in the several groups equal preference in 75 the use of allotted units.

The object of the invention is, therefore, to render allotted switching units equally accessible to operators' positions of all groups of positions.

This object is attained by providing as 80 a feature of the invention a group selector switch associated with the switching unit allotter, which is operated upon the initiation of a call by an operator in any group to select the group in which such operator's 85 position is located.

A further feature of the invention resides in the arrangement of such group selector whereby if calls are simultaneously initiated 90 in two or more groups of positions, an allotted switching unit will become available for the use of the operator in the group of positions nearest to the position the group selector occupies at the instant such calls are initiated. Since the group selector has no 95 definite normal position, the order of preference of the groups of positions in the use of allotted units is thus made variable to give equal preference to all groups of positions, as to the number of allotted units 100 available for the use of each group of positions.

These and other features of the invention will be more obvious from a consideration 105 of the description given hereinafter and of the appended claims.

The accompanying drawings disclose one embodiment of the invention as applied to

circuits of the character disclosed in the aforementioned patent to L. M. Allen.

Fig. 1 shows an allotting mechanism, the group selector of the present invention and the starting circuits of two groups of operators' positions for allotting idle switching units, portions of which are disclosed in Fig. 2, for the use of a calling operator. This figure corresponds to Fig. 8 of the aforesaid application, having additionally the group selector forming the basis of the present invention. Fig. 2 shows in the right hand portion thereof office keys and associated relays of an operator's position in each of two groups of positions; and in the left hand portion thereof two of the operator's position selector switches of one switching unit and certain of the control relays of such switching unit. The apparatus of Fig. 2 is identical with similar apparatus disclosed in Figs. 5 and 6 of the aforesaid application.

For a complete description of the detail construction, relationship and operation of the apparatus disclosed herein, reference may be had to the aforesaid application. To enable a better understanding of the present invention a detailed explanation will now be given with respect to its mode of operation.

It will first be assumed that the allotter 100 is standing in such a position as to allot the switching unit, portions of which are shown in Fig. 2, for the use of the operator in any of the five groups of positions who first initiates a call, that the brushes of the group selector 150 are at the time standing upon the No. 1 terminals of their associated banks and that an operator whose position is the first in group 5, indicated at the right of Fig. 2, initiates a call in response to the request of a calling subscriber for a connection to an automatic office, represented by office key 251.

The operator in response to the request of the calling subscriber depresses the office key 251 corresponding to the desired office, whereupon relays 252 and 253 operate in a circuit (shown in part) extending from battery at the armature and back contact of relay 254, through the right windings of relays 252 and 253, and a contact of the depressed office key. As soon as relay 252 becomes energized, a circuit is closed from battery through resistance 256, the outer contact of relay 255, the outer left armature and contact of relay 252, conductor 122, thence to a point between the lower winding of the balancing coil 113 and the windings of polarized relay 115. The flow of current to ground through the coil 113 and through the windings of polarized relay 115 is in such a direction as to cause said relay to attract its armature. Relay 115 closes a circuit from battery through the right

winding of relay 110, whereupon relay 110 energizes and locks over a circuit extending from battery, through its left winding, inner left armature and contact to ground at the outer left armature and back contact of relay 108.

Relay 110 also establishes an operating circuit for the magnet 151 of group selector 150, which may be traced from battery, through the winding and armature contacts of magnet 151, the outer left armature and front contact of relay 110, brush 152 of selector 150 to ground on the bank terminal on which it is standing. Magnet 151 energizes, interrupting its own operating circuit and advancing the brushes 152, 153, 154, 155, 156 and 157 one step. Brush 152 now engages terminal 158, whereupon a circuit is again established for magnet 151, extending as previously traced to the brush 152, terminal 158, the inner right armature and back contact of relay 109, conductor 124 to ground at the outer right armature and contact of relay 108. Magnet 151 again energizes, interrupting its own circuit and advancing the brushes of switch 150 a second step. Similarly, as the brush 152 engages terminals 159, 160 and 161, the stepping magnet 151 energizes, advancing the brushes of switch 150. When the brush 152 engages terminal 162 there is no effective energizing circuit for magnet 151, since with relay 110 energized, the circuit extending from terminal 162 through the inner right armature and back contact of relay 110 to ground on conductor 124 is open, and therefore the advance of switch 150 is arrested.

A circuit is now established for relay 218 of the allotted switching unit corresponding to the fifth group of operators' positions. This circuit may be traced from battery, through the winding of relay 218, conductor 118, brush 103 of allotter 100, brush 153 of the group selector 150, the inner right armature and front contact of relay 110 to ground on conductor 124. Relay 218, upon energizing, locks over its inner left armature and contact to ground at the armature and back contact of relay 221, and at its outer right armature and front contact establishes a circuit for relay 219. This circuit extends from battery, through the winding of relay 219, the armature and left contact of relay 220 to ground at the outer right armature and contact of relay 218. Relay 219 at its inner right armature establishes an obvious circuit for relay 220, which in turn locks over its left armature and front contact to ground at the outer right armature and front contact of relay 218. Relay 220 also closes two other circuits, one extending from ground through its outer right armature and front contact, the normally closed contacts of relay 223 to battery through the left winding of relay 222,

and the other circuit from ground, through the inner right armature and front contact of relay 220, over conductor 116, brush 102 of allotter 100, the inner right armature and 5 back contact of relay 125 to battery through the winding of relay 108. Relay 108 energizes in this circuit for a purpose which will be described hereinafter. The ground potential applied over conductor 116 also 10 marks the switching unit which has been taken for use as busy to the allotter 100.

Relay 222, upon energizing, locks over its right winding and right armature, through the inner right armature and front contact 15 of relay 218, brush 211 and the normal bank terminal associated therewith to ground at the outer right armature and front contact of relay 218, this locking circuit being maintained until the brush 211 is stepped from 20 its normal position, as hereinafter described. At its left armature and front contact relay 222 establishes an obvious circuit through the right winding of relay 223, and following the energization of relay 223 establishes 25 a circuit through the right armature and front contact of relay 223, the inner right armature and front contact of relay 218 to battery through the winding of stepping magnet 217. Relay 223, upon energizing, 30 locks from ground through its left winding, inner left armature and front contact and the outer right armature and front contact of relay 220.

Stepping magnet 217 of the position selector 200 individual to the fifth group of operators' positions, upon energizing in the previously traced circuit interrupts its own circuit and advances the brushes of the position selector, only one of which brushes is 40 disclosed herein, in the direction indicated by the arrow. As the brushes of the switch advance the test brush 211 tests the condition of the successive operators' positions of the fifth group of positions. The terminals 45 with which brush 211 cooperates, representing non-calling positions, will present a ground potential to brush 211, such ground potential being applied from the normal contacts of position relays similar to relay 252. This ground potential serves to maintain the holding circuit of relay 222 as 50 above traced. When, however, the brush 211 reaches the first position terminal representing the first operator's position, no ground potential will be found thereon due to the energized condition of relay 252, hence the circuit of relay 222 is opened and this relay becomes deenergized, opening in turn the operating circuit of stepping magnet 217, whereby the switch 200 comes to rest. Immediately that relay 222 releases 55 its armatures, a circuit is closed from battery through the right winding of relay 255, the right armature and front contact of relay 252, conductor 259, brush 211, contacts

of relay 218, the right armature and back contact of relay 222, the outer right armature and front contact of relay 219, to ground at the outer left armature and front contact of relay 223. Relay 255 closes a 70 locking circuit for itself and at its outer left armature disconnects battery from conductor 122 and the balancing coil 113. The selected operator's position is maintained busy to other position selectors by ground potential applied over the brush 211, from the outer left armature and front contact of relay 223.

After the operator has completed the setting up of the desired line designation upon 80 her keyboard (not shown), relay 219 becomes unlocked and opens the holding circuit of relays 252 and 253, which thereupon deenergizes. This holding circuit of relays 252 and 253 may be traced from battery 85 through the armature and contact of relay 254, left windings of relays 253 and 252, front contacts of relay 252, conductor 250, brush 211, contacts of relay 218, right armature and back contact of relay 222, the 90 outer right armature and front contact of relay 219 to ground at the outer left armature and front contact of relay 223. At its outer left armature and back contact 95 relay 219 also establishes a circuit for relay 222 extending through the left winding of this relay, the outer left armature and back contact of relay 219, the inner right armature and front contact of relay 218, brush 211, conductor 250, to ground at the normal contact of the right armature of relay 252. Relay 222, on energizing, locks over its right winding and right armature, thence over the circuit just traced to ground 100 at the armature contact of relay 252. With relay 222 energized, the previously traced circuit is established for the stepping magnet 217, which magnet immediately opens its own circuit, stepping the brushes of the switch 200 forwardly from terminal to 105 terminal. Relay 222 is maintained energized in each position of switch 200 by ground potential on the terminal with which brush 211 cooperates extended from the normal right hand contacts of relays similar to 110 252 at non-calling operators' positions. When the switch 200 reaches the next to its normal position, a circuit is closed from battery, through the right winding of relay 222, right front contact of said relay, front 115 contacts of the inner right armature of relay 218, brush 211, winding of relay 221 to ground. Relay 221 opens the holding circuit of relay 218, which relay becomes deenergized and opens the circuit of relay 220. Relay 218 on deenergizing completes a 120 circuit from battery, through the winding and contact of magnet 217, inner right armature and back contact of relay 218, brush 211, outer right armature and back contact 125 130

of relay 220 to ground. Stepping magnet 217 interrupts its own circuit once more and advances the brushes of switch 200 to their normal position terminals. Following the de-energization of relay 220, relay 223 is unlocked and relay 222 releases its armatures. The other apparatus of the operator's position and the apparatus of the switching unit which has been employed are restored to normal as soon as their functions have been completed in the manner fully set forth in the aforesaid application.

At the time relay 218 energized, battery potential was connected over conductor 232, the outer left armature and front contact of relay 218, conductor 117, to a point between the upper coil 113 and the windings of polarized relay 115, balancing the polarized relay and causing its deenergization. The initial energizing circuit of relay 110 is now opened, but relay 110 is maintained locked over its locking winding until relay 108 energizes, which occurred, as previously described, upon the energization of relay 220. Upon the energization of relay 108 a circuit is established for the stepping magnet 101 of the allotter 100 for the purpose of advancing the brushes 102 to 107, inclusive, of the allotter to allot a new switching unit for the use of the next calling operator. The circuit of magnet 101 may be traced from battery through the winding and armature contact of the magnet, the inner right armature and front contact of relay 108, the inner right armature and back contact of relay 125, brush 102, conductor 116 to ground at the inner right armature and front contact of relay 220 of the switching unit employed by the operator of group 5, as previously described. Magnet 101 energizes interrupting its own circuit and advancing the brushes of the allotter one step. If the next switching unit is busy, ground potential is encountered by the brush 102 and the stepping magnet 101 of the allotter again energizes, advancing the brushes of the allotter a second step. This continues until the brush 102 encounters the test terminal of an idle switching unit, when the brushes of the allotter are arrested and brushes 103 to 107, inclusive, associate conductors leading to the group relays corresponding to relays 208, and 218 of such allotted switching unit with the brushes 153 to 157 of the group selector 150.

If calls in different groups are initiated simultaneously, for example, calls in the first and fifth groups of positions, the polarized relays 114 and 115 of such groups will both energize and cause the locking up of corresponding relays 109 and 110. When, therefore, the group selector 150 is started, for example, from the position in which it is shown standing, the calling position in the first group will be given preference in the

use of the allotted switching unit since the brush 152 will encounter terminal 158 first and operate the position selector start relay 208 of the first group. As soon as the switching unit becomes assigned to the use of the operator in the first group, the group selector 150 will again advance under the control of relays 115 and 110 and cause the operation of the start relay 218 of another allotted switching unit, in the manner previously described. Thus the group of positions first found by the group selector 150 becomes the first served and since each group of positions has four appearances in the banks of switch 150, each group of operators is therefore given equal preference in the use of allotted switching units, that is, the same number of switching units are available for the use of each of the five groups of operators' positions. The use of the group selector precludes the possibility of any one group of operators' positions (20 positions) monopolizing all of the available allotted switching units, for each group of operators' positions cannot appropriate to its own use at one time more than four allotted switching units.

If an undue delay occurs in the allotment of a new switching unit, provision is made for causing the operation of the allotter 100 without awaiting the operation of relay 108. This is accomplished in the following manner: Upon the energization of any of the relays 109, 110, etc., a circuit is established from ground, through the interrupter 128, the outer right armature and front contact of one of the relays 109, 110, etc., the right armature and back contact of relay 126, winding of relay 127 to battery at the inner left armature and back contact of relay 108. Relay 127, upon energizing, locks itself up in series with relay 126 from battery, through the inner left armature of relay 108, windings of relays 127 and 126 to ground at the armature contact of relay 127. Relay 126 energizes in this locking circuit as soon as the interrupter 128 reaches a non-circuit closing position. With relay 126 energized as soon as the interrupter 128 again reaches a circuit closing position, a circuit is established through the left armature and contact of relay 126, through the winding of relay 125 to battery. Relay 125, upon energizing, closes a circuit from battery, through the winding of stepping magnet 101, to ground through the outer right armature and contact of relay 125, this circuit being maintained until the interrupter 128 reaches the next non-circuit closing position, when relay 125 deenergizes, in turn causing the deenergization of stepping magnet 101 and the advance of the brushes of the allotter one step. Relay 125 also closes a circuit for relay 108 extending from battery, through the winding of relay 108, the

inner armatures and front contacts of relay 125, the left armature and contact of relay 126 to ground through the interrupter 128. Relay 108, upon energizing, opens the holding circuit of relays 126 and 127, whereupon these relays deenergize. Relay 126 upon deenergizing, opens the previously traced circuit of relay 125 preventing the reenergization of relay 125 when the interrupter 128 again reaches a circuit closing position. With relay 125 deenergized and relay 108 energized, a holding circuit is established for relay 108 extending through its winding, the inner right armature and back contact of relay 125 to the brush 102 of the allotter, this holding circuit being maintained as long as the brush 102 engages test terminals of busy switching units. As long as the relay 108 is maintained energized, the circuit of stepping magnet 101 is maintained as previously described to advance the brushes of the allotter in search of an idle switching unit.

What is claimed is:

- 25 1. In a telephone system, a plurality of groups of operators' positions, a plurality of switching units, means for allotting a switching unit for the use of any operator, and means for giving each group of operators' positions equal preference in the use of allotted switching units.
- 30 2. In a telephone system, a plurality of groups of operators' positions, a plurality of switching units, means for allotting a switching unit for the use of any operator, and a group selector for selecting the group of positions in which a calling operator is located and for associating such group of positions with an allotted switching unit, said group selector being arranged to give each group of operators' positions equal preference in the use of allotted switching units.
- 35 3. In a telephone system, a plurality of groups of operators' positions, a plurality of switching units, each including as many position selector switches as there are groups of positions, means for allotting a switching unit for the use of any operator, and means operative upon the initiation of a call by any operator to select the group in which the calling position is located and to start a position selector to associate the calling position with an allotted switching unit.
- 40 4. In a telephone system, a plurality of groups of operators' positions, a plurality

of switching units, each including as many position selector switches as there are groups of positions, means for allotting a switching unit for the use of any operator, and a group selector switch operative upon the initiation of a call by any operator to select the group in which the calling position is located and to start a position selector to associate the calling position with an allotted switching unit.

5. In a telephone system, a plurality of groups of operators' positions, a plurality of switching units, means for allotting a switching unit for the use of any operator, a group selector, test leads from each of said groups of positions terminating in rotation and each with a plurality of appearances in the bank of said selector, and means under the control of any operator for starting said selector to associate the group of positions in which said operator's position is located with an allotted switching unit.

6. In a telephone system, a plurality of groups of operators' positions, a plurality of switching units, means for allotting a switching unit for the use of any operator, means for associating an allotted switching unit with an operator's position of any of said groups, means effective thereafter for operating said allotting means to allot another switching unit for use, and means automatically effective after the elapse of a definite time interval for operating said allotting means in the event of a delay in associating the calling operator's position with an allotted switching unit.

7. In a telephone system, a plurality of groups of operator's positions, a plurality of switching units, means for allotting a switching unit for the use of any operator, a group selector for selecting the group of positions in which a calling operator is located and for associating such group of positions with an allotted switching unit, means effective thereafter for operating said allotting means to allot another switching unit for use, and means automatically effective after the elapse of a definite time interval for operating said allotting means in the event of a delay in associating a calling operator's position with an allotted switching unit.

In witness whereof, I hereunto subscribe my name this 27th day of June A. D., 1923.

ROBERT W. HARPER.
